Patented June 14, 1921.

UNITED STATES PATENT OFFICE.

RICHARD A. DIADUL, JR., OF CHICAGO, ILLINOIS.

ORTHOPEDIC APPLIANCE.

1,381,290.

Specification of Letters Patent. Patented June 14, 1921.

Application filed September 30, 1920. Serial No. 413,702.

To all whom it may concern:

Be it known that I, RICHARD A. DIADUL, Jr., a citizen of the United States, and a resident of Chicago, in the county of Cook 5 and State of Illinois, have invented certain new and useful Improvements in Orthopedic Appliances, of which the following is a specification.

This invention relates to improvements 10 in orthopedic appliances and like devices for correcting deformities of the foot and other parts of the human body, and more particularly to a novel construction for the metallic brace or supporting members thereof.

15 In the usual type of corrective appliances, the brace members are ordinarily articulated or hinged together in order that the parts may yield with the bodily movements, or may be adjusted to the particular deformity 20 or necessary correction therefor. An orthopedic appliance, as its name suggests, is a device for correcting deformities of the human foot, and is preferably designed to be worn beneath the shoe of the wearer, and for 25 this reason it is desirable that the parts be constructed with a view of avoiding, so far as possible, projecting or otherwise prominent members which not only produce a cumbersome structure, but cause discomfort to 30 the wearer and attract attention to the presence of the corrective appliance.

Among the objects of the present invention is to provide a construction for a locking device, associated with the hinged brace 35 members, and utilized in locking said members in one of several adjusted positions. A preferred form of an appliance to which the invention is readily applicable is herein- 40 after more fully described and clearly illustrated in the accompanying drawings, in which—

Figure 1 is a perspective view of an orthopedic appliance embodying the novel features of the invention,

45 Fig. 2 is an enlarged view in side elevation of the articulated joint showing the locking device in unlocked position,

Fig. 3 is a view in vertical section taken on line 3—3 of Fig. 2, and

50 Fig. 4 is a view similar to Fig. 3 showing the parts adjusted in a different position, and locked.

The appliance herein illustrated, and embodying the invention, comprises in general 55 a metallic vertical brace or upright 1, to which is connected by means of a joint here-

inafter to be described, a metallic plate or shoe 2 adapted to extend beneath and support the arch of the foot. Secured to the plate 2 by means of rivets or the like is a 60 leather shoe 3 adapted to be laced about the heel and ankle portions of the foot. Attached to the upper end portion of the vertical brace 1 are two semi-circular bands 4—4 which carry a leather sleeve or lacing 65 5 adapted to surround the limb immediately above the ankle. The appliance herein shown is designed for the right foot, the parts being so arranged that the metallic brace is located on the inside of the foot 70 and ankle.

The metallic plate 2 is reinforced by means of a hinge-plate 6 secured to the outside thereof, to which the vertical brace member 1 is directly connected through the 75 medium of a joint or hinge formed in the following manner:

Pivoted to the upper end of the hinge-plate 6 is a hinge-block 7, said plate 6 and block 7 being provided with co-acting portions 6^a and 7^a respectively, of reduced thickness, and circular conformation, through which a pivoted pin 8 extends. In this manner a joint is formed between the hinge-plate 6 and hinge-block 7, permitting the 85 relative movement of the latter in the plane of the vertical brace member, thereby permitting the flexing of said brace member with respect to the relatively fixed plate 2, in the same manner as the parts of the foot 90 are flexed in walking.

The hinge-block 7 is interposed between the hinge-plate 6 and the vertical brace 1, the latter being provided at its lower end with cylindric formed ears 9 which are 95 spaced apart, and include between them a similarly formed knuckle 10 integral with the hinge-block 7. Extending through the co-acting ears 9 and knuckle 10 is a hinge pin 11, the same extending horizontally and 100 at right angles to the pivoted pin 8, the parts forming the upper joint just described being so arranged as to permit a relative rotative movement between the hinge-block 7 and the vertical brace 1 in a right angle to the plane 105 of flexing movement afforded by the lower joint. In short, a so-called "double joint" is formed in the brace at a point corresponding to the ankle of the foot to be corrected.

Referring now in detail to the locking device, the same consists of parts associated with the brace member 1, and the hinge-

block 7, these parts being constructed and arranged in the following manner:

A locking lever 12 is pivotally mounted at the lower extremity of the vertical brace member 1, and consists of a flat metal bar formed to provide a head 12^a and a handle 12^b. Extending through the center of the head 12^a of the locking member is a screw 13 anchored in the brace member 1, and serves 10 as a pivot for the locking member. As clearly shown in Fig. 1, the locking member 12 extends longitudinally of the brace member 1, and shaped so as to normally lie flatwise against the outer surface thereof when 15 in locked position. The lower end surface of the head 12^a of the locking member 12 terminates in close proximity to the surface of the knuckle 10 of the hinge-block 7, said end being preferably curved or rounded, the center of curvature being the screw 13. Formed 20 on the curved end surface of the head 12^a of the locking member 12 is a series of parallel teeth 14 and upon the opposed surface of the knuckle 10 and extending longitudinally thereof, are formed a series of parallel 25 teeth or ribs 15, forming a toothed sector extending throughout the upwardly facing surface thereof, the number or extent of the teeth 15 being determined by the amount 30 of relative adjustment or flexing of the brace 1.

As clearly shown in Fig. 3, the teeth 15 are cut at a slight angle; that is, slightly oblique to the axis of rotation of the locking 35 lever 12, and to the teeth 14, so that when the teeth are engaged by the rotation of the locking lever into vertical position, wedging action is produced which securely locks the members and eliminates any lost motion that 40 might be present.

With the parts arranged as shown in Fig. 1, the vertical brace 1 is securely locked to the hinge-block 7 so that relative movement between these parts is prevented, although 45 free flexing between the brace member 1 and the plate 2 is permitted through the medium of the lower joint or hinge between the hinge-plate 6 and hinge-block 7. Assuming now that it is desired to adjust the brace member 1 laterally with respect to the plate 2, the locking lever 12 is rotated forwardly 50 to the position shown in Fig. 2, whereby the teeth 14 and 15 are disengaged and the brace member 1 is free to be revolved with respect to the hinge-block 7, and having been adjusted 55 to the desired position, as, for instance, to the position shown in Fig. 4, the locking lever 12 is again revolved to its upright position whereupon other teeth come 60 into engagement, and the locking of the parts is effected. Manifestly, the locking is accomplished through the medium of the teeth 14 and 15, which engage each other much 65 in the same manner as two threaded members, the slight obliquity of the threads of

the locking lever producing the wedging action heretofore referred to, with the result that the teeth become tightly jammed when the lever is moved into locking position. In order to assure the retention of the locking lever in locking position, however, a sliding sleeve or band 16 is mounted upon the vertical brace member 1, and is adapted to be forced downwardly over the handle 12^b of the locking lever 12 when the same is in locking position, and similarly to be moved upwardly in order to release the handle when it is desired to rotate the locking lever into unlocking position.

It is to be observed that the locking lever 80 lies flatwise against the brace, and substantially flush therewith, thus occupying a very small space, and hence neither increases the mass to be concealed by the shoe of the wearer, nor does it form an awkward projection increasing the unsightliness of the appliance. The use of intermeshing teeth provides a positive locking, and at the same time affords a simple and efficient means of 85 accomplishing the desired degree of adjustment. The use of teeth in the nature of screw threads has a distinct advantage not only in the simplicity involved, but also because of the minute adjustments that may be secured. Clearly the number and pitch 90 of the teeth determines the limits of adjustment, and these may be varied to suit the particular appliance.

Although I have described a preferred embodiment of the invention, it is to be understood that it may be readily applied to other types of appliances, as well as used in modified form, without departing from the spirit of the invention. Therefore I do not wish to be limited except in so far as the invention is more specifically pointed out in the appended claims.

I claim as my invention:

1. In an orthopedic appliance or the like, the combination of two hinged together members, a locking member pivotally mounted on one of said hinged members, and adapted to be moved into and out of locking engagement with the other hinged member, and means acting to frictionally retain 110 said locking member in locked position.

2. In an orthopedic appliance or the like, the combination of two members hinged together, and means for locking said members from relative movement, comprising a lever pivotally mounted on one of said hinged members, and provided with locking members adapted to have locking engagement with complementary locking members on the other of said hinged members.

3. In an orthopedic appliance or the like, the combination of a plate member, a brace member hinged to said plate member, and means for locking said plate and brace members, comprising a locking lever pivoted to 130

one of said members, said lever and the other member being provided with co-acting locking teeth arranged substantially parallel with the direction of movement of said locking lever.

4. In an orthopedic appliance or the like, the combination of a plate and brace members pivotally connected together to permit the flexing of the members in one direction, 10 and means for locking the parts in any of several flexed positions, comprising a lever mounted on one of said members, and provided with a toothed surface adapted to engage a toothed surface of the other of said members.

5. In an orthopedic appliance or the like, the combination of a plate and brace members pivotally connected together to permit the flexing of the members in one direction, 20 and means for locking the parts in one of several flexed positions, comprising a lever mounted on one of said members, and provided with locking teeth arranged substantially transverse to the plane of flexing, and 25 adapted to be moved into and out of locking engagement with a series of locking teeth on the other of said members.

6. In an orthopedic appliance or the like, the combination of two brace members 30 hinged together by means of a pin and knuckle connection, and a lever pivotally mounted on one of said members, said lever and the knuckle of the other hinged member being provided with co-acting teeth.

35 7. In an orthopedic appliance or the like, the combination of two members hinged together, and means for locking said members

from relative movement, comprising a lever pivotally mounted on one of said members and provided with a toothed surface, and 40 adapted to engage a toothed surface of the other of said members, the teeth of one surface being oblique to the plane of rotation of said lever.

8. In an orthopedic appliance or the like, 45 the combination of two members hinged together through the medium of a pin and knuckle connection, and means for locking said members from relative movement, comprising a lever pivotally mounted on one of 50 said members and provided with a toothed edge, and adapted to engage a toothed surface of the knuckle of the other of said members, the teeth of said lever being arranged obliquely to the plane of rotation. 55

9. In an orthopedic appliance or the like, the combination of two brace members, a block interposed between said brace members, and having pivotal connection therewith to permit flexing in two directions, and 60 means for locking said brace members from flexing in one direction, comprising a series of parallel teeth on said block and arranged transversely to the direction of flexing of one of said brace members, and a lever pivoted to said last mentioned brace member, and comprising a toothed surface adapted to be brought into and out of locking engagement with said teeth of the block in the rotative movement of said lever. 65

In witness whereof, I hereunto subscribe my name this 28th day of September, A. D. 1920. 70

RICHARD A. DIADUL, JR.
